UNITED STATES PATENT OFFICE.

BASCOM O. AUSTIN, OF WILKINSBURG, PENNSYLVANIA, ASSIGNOR TO WESTINGHOUSE ELECTRIC & MANUFACTURING COMPANY, A CORPORATION OF PENNSYLVANIA.

OVERLOAD RELAY.

Application filed January 30, 1923. Serial No. 615,832.

My invention relates to overload trip switches and it has special relation to switches adapted to be mounted on the dashes of trolley busses or the like.

5 An object of my invention is to provide a switch of the above-mentioned character that is adapted to be actuated from two independent sources.

Another object of my invention is to provide, in a switch mounted upon one side of a panel board and adapted to be actuated automatically in response to predetermined values of current, manually controlled means, located upon the other side of the 15 panel board, for actuating the switch independently of the automatic means.

A more specific object of my invention is to provide an automatic switching mechanism adapted to be placed on the opposite side of the dash of an electric vehicle, or the like, from the operator and having control means extending through the dash whereby the switching member may be actuated manually by the operator if so desired. The device may be used as a relay for operating a line switch.

Other objects, as well as details of construction whereby my invention may be utilized, will be apparent from the following 30 description, taken in conjunction with the accompanying drawings, wherein

Figure 1 is a view, mainly in side elevation but partly in section, of a switch constructed in accordance with my invention,

35 Fig. 2 is a bottom plan view of the switch shown in Fig. 1, and

Fig. 3 is a view, in front elevation, of the switch shown in Fig. 1.

Referring to the drawing, a switch 1 is mounted upon a panel board 2 in any suitable manner, as, for example, by bolts 3. The panel board 2 is secured, in any suitable manner, to the rear side of the dash 4 of a trolley bus, or the like. The switch 1 embodies a coil 5 that is secured within a supporting bracket 6, a core member 7 operating within the coil 5 and controlled thereby, a dash-pot 8 for governing the action of the core member 7, and a switch member 9.

50 The switch member 9 is pivotally mounted upon the supporting bracket 6 and is provided with a contact member 11 for bridging two stationary contact members 12 and 13, which are mounted upon the panel board 2, when the switch is in its closed posi-

tion. The switch member 9 is also provided with a projecting portion 15 adapted to be engaged by a latch 16, for a purpose to be hereinafter set forth. A spring member 17 is provided for normally maintaining 60 the switch member 9 in a position to bridge the contact members 12 and 13.

An arm 18 is pivotally mounted upon the supporting bracket 6 and has latch 16 formed on one end and a depending arm 65 19 on the other end thereof. A spring 21 biases the latch 16 toward engagement with the switch member 9.

A push-button 22 is arranged on the opposite side of the dash 4 that is, on the side 70 adjacent the operator, from the switch member 9. A rod 23, preferably of some insulating material, is secured to the push-button 22 and extends through the dash 4 and panel-board 2 to a position adjacent the 75 center of bridging contact member 11. A spring 24 biases push-button 22 and rod 23 away from engagement with contact member 11.

A manually operable rod 25 extends 80 through the dash 4 and panel-board 2. A round bar 26, of larger diameter than the rod 25, is threaded to the rod 25 and is secured against rotation relative thereto by a rivet 27. A transverse slot 27 is cut in the 85 end of the bar 26 to receive one end of a link 29. A longitudinal slot 31 is cut in the link 29. A cotter-pin or other securing means is inserted through the end of the bar 26 and slot 31, thus providing a lost-motion connection between bar 26 and link 29. The other end of link 29 is pivotally secured to a projection 32 of the supporting bracket 6. One end of the rod 25 projects through the panel-board 2 and the dash 4, and is provided with 90 a knob 33 that is detachably secured thereto by means of threads 34 and set-screw 35. A spring 36 normally biases link 29 away from engagement with the arm 19.

The operation of my invention may be set 100 forth as follows: When the current traversing coil 5 reaches a predetermined value, corresponding to an overload on a driving motor, the movable core 7 is actuated and serves to trip the movable switch member 9 105 and move the bridging member 11 out of engagement with the contact members 12 and 13, thus breaking this auxiliary circuit and causing the interruption of the motor circuit 110 in accordance with a familiar practice.

Upon the switch member 9 assuming its open position, the latch 16 engages the projecting portion 15 of the switch member 9 and maintains the switch in its open position against the action of the spring 17.

In case it is desired to reset the switch, the operator grasps the knob 33 and pulls the rod 25 against the action of the spring 36. The link 29 is thus actuated into engagement 10 with the depending arm 19 to cause the disengagement of latch 16 from the projection 15 of the switch member 9. The switch member 9 is then actuated by the spring 17 to its closed position, whereby the movable contact member 11 again bridges the contact members 12 and 13. The spring 36 will return the rod 25 and knob 33 to their initial position upon release of the knob by the operator.

20 If the operator wishes, at any time, to break the circuit through contact members 12, 11 and 13, he may press the push-button 22. The rod 23 will then engage the bridging contact member 11 and actuate the switch member 9 to its open position, whereupon the latch 16 will operate as described above. The spring 24 will return the rod 23 and push-button 22 to their initial positions when the operator's hand is removed from the 30 push-button. The switch may be reset as described above.

An advantage of my invention is that the main mechanism of the switch may be placed near the motor and control apparatus, thus 35 conserving space on the inside of the dash, and still be under the control of the operator.

Still another advantage of my invention is that, in addition to the automatic operation of the switch under predetermined conditions, the operator may, at any time, operate the switch without leaving his usual station.

It will be understood that the switch mechanism shown and described is purely illustrative and that various modifications may be made therein without departing from the spirit and scope of my invention. I desire, therefore, that only such limitations shall be imposed as are indicated in the appended 50 claims.

I claim as my invention:

1. A switch mechanism comprising a plurality of stationary contact members, a movable contact member cooperating therewith, means for normally biasing said movable contact member toward engagement with said stationary contact members, electro-re-

sponsive means for effecting disconnection of said contact members, and manually operated means for effecting disconnection of 60 said contact members independently of said electro-responsive means.

2. A switch mechanism comprising a panel board, a switch member mounted upon said board, means for biasing the switch member toward its closed position, electro-responsive means for actuating the switch member to its open position, a latch for maintaining the switch member in its open position, a rod extending through said panel board, a link 70 pivotally secured to said bar for releasing said latch upon actuation of said bar, and a push button upon the opposite side of said panel board for actuating said switch member independently of said electro-responsive 75 means.

3. A switch mechanism comprising, in combination, a panel board, stationary and movable switch members carried by the panel board, means adapted to urge continuously 80 the movable switch member toward the stationary switch members, electro-responsive means adapted to move said movable switch member out of contact with the stationary switch members, latch means disposed to engage the movable switch member when operated by the electro-responsive means, manually operable means for actuating said movable switch member independently of the electro-responsive means, and manually operable 85 means for releasing the latching means.

4. A switch mechanism comprising, in combination, a panel board, stationary and movable switch members carried by the panel board, means adapted to urge continuously 95 the movable switch member toward the stationary switch members, electro-responsive means adapted to move said movable switch member out of contact with the stationary switch members, latch means disposed to engage the movable switch member when operated by the electro-responsive means, manually operable means for actuating said movable switch member independently of the electro-responsive means, and manually operable 100 means for releasing the latching means, said latching means being disposed to cooperate to retain the movable switch member in contact with the stationary switch members.

In testimony whereof, I have hereunto subscribed my name this 25th day of January, 1923.

BASCUM O. AUSTIN.
